UNITED STATES PATENT OFFICE.

THORNTON P. HURD, OF VALPARAISO, INDIANA.

WINDOW-SHADE-ROLLER-SUPPORTING MEANS.

Application filed August 2, 1924. Serial No. 729,831.

To all whom it may concern:

Be it known that I, THORNTON P. HURD, a citizen of the United States, residing at Valparaiso, in the county of Porter and State of Indiana, have invented certain new and useful Improvements in Window-Shade-Roller-Supporting Means, of which the following is a specification.

This invention relates to window shade roller supporting means and has for its primary object the provision, in a manner as hereinafter set forth, of a shade roller support adapted to be countersunk into the inner face of a window frame, and having 10 means whereby a portion of the countersunk member may be forced back into the frame by the end of the window shade stick to allow the other end of the stick to be brought into position in a slotted holder on 20 the opposite side of the frame, said means being spring pressed to follow the end of the window shade stick out to support the same in position within the window frame.

A further object of the invention is the 25 provision, in a manner as hereinafter set forth, of a window shade supporting fixture which will be inconspicuous, strong, durable, and permanent when placed in position, and inexpensive to manufacture and fit 30 into place.

The invention will be best understood from a consideration of the following detailed description taken in connection with the accompanying drawings forming a part 35 of this specification, with the understanding that the invention is not confined to any strict conformity with the showing of the drawings, but may be changed and modified so long as such changes and modifications 40 mark no material departure from the salient features of the invention as expressed in the appended claims.

In the drawings:

Figure 1 is a side elevation of the upper 45 portion of a window frame showing a shade suspended therein by means of the fixture constructed and applied in accordance with this invention.

Figure 2 is a longitudinal section through 50 one portion of the device.

Figure 3 is a face view of the same.

Figure 4 is a plan view of another part 55 of the device, and

Figure 5 is a side elevation of the same.

Referring now to the drawings in detail 60 wherein like numerals of reference indicate

corresponding parts throughout the several views, the shade roller supporting fixture embodying this invention comprises two members, a stationary plate member 1 and 60 a countersunk member indicated as a whole by the numeral 2. The member 1, as shown, comprises a circular plate having a centrally positioned elongated slot 3 therein and further having formed integral with and extending in the same direction from the periphery thereof a series of spurs 4. This plate member 1 is secured in position by directing the points of the spurs 4 against the inner face of one side of the frame 5 65 adjacent the top thereof as shown in Figure 1 and driving the points 4 into the inner face of the frame until the plate 1 abuts the inner face.

In the other side of the frame 5 directly 70 opposite the plate 1 an aperture is formed to receive the member 2. This member comprises an outer relatively shallow cylindrical portion 6 having the front end open and having extended from the rear end the 75 substantially elongated tubular portion 7 which is closed at its rear end as at 8 and has its forward portion open and opening into the cylinder 6. This tubular portion 8 has a longitudinal slot 9 formed in the wall 80 thereof from the rear end 8 to a point approximately half the length of the tube. The tubular member 7, as shown, is centrally positioned upon the rear end of the 85 cylinder 6.

Slidable longitudinally in the tubular member 7 is a sleeve 10, open at both ends and provided at its rear end with a down-turned finger 11, which is adapted to extend 90 into the slot 9 to ride therein to guide the sleeve 10. The forward end of the sleeve 10 has secured thereto the disc 12, which has a central aperture 13 therein, and positioned 95 within the sleeve 10 and having one end bearing against the end partition 8 of the tubular member 7 and having its other end bearing against the disc 12 is a helical spring 14, which as shown, tends to maintain the sleeve in its maximum projected position, which position brings the outer 100 face of the disc 12 flush with the edge of the cylinder 6 at its open end, as shown in Figure 2.

The member 2 as is shown in Figures 1 and 2 is countersunk in the inner face of the 110 window frame 5 as before stated, and when so positioned is inconspicuous. When it is

desired to place the roller of the window curtain 15 in the frame 5, the end having the round pin 16 therein, is inserted first into the aperture 13 of the disc 12, as the disc is forced back into the cylinder 6 against the tension of the spring 14 until the squared end 17 of the roll can be moved into position between the inner faces of the frame and in alignment with the aperture 3 in the plate

10 1. The spring 14 is then allowed to press the plate 12 out to force the shade rod or roller over to seat the squared end 17 in the aperture 3 where it will be securely retained by means of the spring 14. The pin 16 turns freely in the aperture 13, whereas the squared pin 17 is held from turning in the aperture 3 when the shade is drawn down, to put under tension the spring which is contained in the shade roller.

15 From the foregoing description, it may be seen that a novel and efficient shade fixture is provided which is simple in structure, yet neat and efficient in action.

Having thus described my invention what 20 I claim is:

1. A curtain shade roller support adapted to be sunk into the inner face of a window frame, comprising a cylindrical member having a relatively long rear portion closed 25 at one end and a shallow front portion opening thereinto of greater diameter and further being open at its front end, each portion being of constant diameter throughout, an inner member comprising a relatively 30 long cylindrical portion of a diameter to snugly telescope into said long rear portion, a flat annular head having a central aper-

ture therein for the reception of a shade roller pin secured to the end of said cylindrical portion and adapted to snugly reciprocate in said shallow portion, and an expandable spring housed within said cylindrical portion and having one end bearing against the closed end of the said rear portion.

2. A curtain shade roller support adapted to be sunk into the inner face of a window frame, comprising a cylindrical member having a relatively long rear portion closed at one end and a shallow front portion opening thereinto of greater diameter and further being open at its front end, each portion being of constant diameter throughout, an inner member comprising a relatively long cylindrical portion of a diameter to snugly telescope into said long rear portion, a flat annular head having a central aperture therein for the reception of a shade roller pin secured to the end of said cylindrical portion and adapted to snugly reciprocate in said shallow portion, and an expandable spring housed within said cylindrical portion and having one end bearing against the closed end of the said rear portion, said long rear portion having a longitudinally extending slot cut therein, and means formed from said cylindrical portion at the rear end thereof to provide a depending finger slidable in said slot to guide the inner member.

35 In testimony whereof, I affix my signature hereto.

THORNTON P. HURD.
